UNITED STATES PATENT OFFICE.

AARON P. GOULD, OF CANTON, OHIO.

SURGICAL CHAIR.

SPECIFICATION forming part of Letters Patent No. 397,077, dated January 29, 1889.

Application filed December 10, 1887. Serial No. 257,543. (No model.)

To all whom it may concern:

Be it known that I, AARON P. GOULD, a citizen of the United States, and a resident of Canton, county of Stark, State of Ohio, have invented a new and useful Improvement 5 in Surgical Chairs, of which the following is a full, clear, and exact description, reference being had to the accompanying drawings, making part of this specification.

10 My invention relates to improvements in surgical chairs, and particularly to providing means for raising and lowering the body of the chair vertically, and to rotate and rock said body on the supporting-base.

15 With these ends in view my invention consists in certain features of construction and combinations of parts, as will be hereinafter described, and set forth in the claims.

Figure 1 is a view in perspective of a surgical chair illustrating my invention. Fig. 2 is same view with the parts detached, comprising the base, vertical slide, circular way, and rotary body-support, and back, seat, and leg-rest frame, which will be hereinafter lettered and explained. Fig. 3 is a view in perspective of parts detached and enlarged, comprising the lifting-lever. Fig. 4 is a view of parts shown on the under side of the seat, comprising the seat lifting and lowering mechanism and seat-hinge, and means whereby the two parts may be held horizontally parallel. Fig. 5 is a side elevation, and Fig. 6 a view in perspective, comprising a section of arm-support, slide, and adjustable cushion-board.

35 Similar letters of reference indicate corresponding parts in all of the figures of the accompanying drawings.

The base A (see Fig. 1) is formed of two A-frames coupled by a strut, a, and having on 40 their inner face vertical grooves a', into which the slides a² of frame B are fitted for vertical movement, said frame having lugs a³, to which the locking-frame a⁴ has a pivotal connection, and a downwardly-projected lug, a⁵, 45 through which the spring-supporting rod a⁶ passes, (see Fig. 3,) and against which the ends of the coil-springs a⁷ rest, forming a buffer to arrest or prevent a jar when the body of the chair is quickly moved or swung 50 about its pivotal connection with the frame

B. To the downwardly-projected lug a⁸ the upper end of the rack a⁹ is pivotally secured, the lower end of the said rack being pivotally secured to the hoisting-lever C, as shown at a¹⁰. There are also provided vertically-projected lugs b, having perforations that correspond with perforations b' in the frame of the circular way D, for a pivot or bolt, whereby a pivotal connection, x, is formed between the frame B and the circular way D. The circular body-supporting frame E is pivotally secured to the circular supporting-way D by a bolt passed through the centrally-located perforations b². The frame E, as it rests on the circular-way D, is prevented from making an 65 entire revolution thereon by means of lugs d³ on the way D, which occupy positions in the path of downwardly-projected portions c⁹ of the frame E.

A depending rack-frame, F, is secured to 70 the way D by bolts or rivets passed through the perforations b³ in the way D and b⁴ in lugs in upper end of frame F. (See Figs. 3 and 5.)

To raise the frame vertically in the grooves a' in the base, a foot-lever, C, is provided, of 75 the form substantially as shown in Fig. 3, and pivotally secured to the strut a, or to the plate b⁵, which is secured to the strut. The foot-lever C is formed of two parallel bars, b⁶, joined by the loop-frame b⁷ and web b⁸. A 80 spring-actuated locking-bolt, b⁹, is placed between the bars b⁶, the inner end passed through the loop b⁷ and engaging the rack a⁹, the outer end pivotally secured to a depending lug c, as shown at c¹, integral with a pedal, 85 c', which is pivotally secured to the outer end of lever C at c². The locking-bolt b⁹, because of its support near one end in the loop b⁷ and its pivoted connection at its opposite end with the pivoted step c', has a limited endwise 90 movement relatively to the lever C. It is drawn out of engagement with the rack a⁹ by tilting the step c' over toward the front of the chair, while a coil-spring, c³, is provided, as shown, the energy of which is exerted to 95 hold the locking-bolt in engagement with the rack a⁹. A coil-spring, c⁴, resting on the outer end of the lever C and under the frame a⁴, is provided, the energy of which is exerted to hold the lock in engagement with the rack F. 100

To raise the frame B and the body of the chair vertically, the foot is placed on the pedal c' , and by rocking the pedal over its pivotal connection with the end of the lever 5 C the locking-bolt b^9 will be disengaged from the rack a^9 , when the lever C may be pressed down, rocking the lever over its pivotal connection with the strut a , raising the rack a^9 by its pivotal connection a^{10} therewith. The 10 upper end of the rack being pivotally secured to the frame B, the said frame and the body of the chair may be raised and lowered, the spring c^8 throwing the bolt b^9 into engagement with the rack when the foot is removed 15 from the pedal.

To rock the body of the chair over the base A on the pivotal connection of the way D with the frame B, the foot is placed on the pedal c^5 , pressing the locking-frame down, 20 thereby disengaging the lock c^6 from the rack F, releasing the body of the chair, so that it may be tipped forward or back, and by the use of the locking-frame may be secured in desired adjustment. The springs a^7 , 25 resting between the lugs c^7 and on the lug a^5 , will prevent the body falling violently to either limit of its movement.

The body-supporting frame E may be rotated about its vertical central pivot, resting 30 on the way D and fixed in adjustment by a turn-bolt, c^{10} . (Shown in Fig. 5.)

The back section, G, is pivotally secured to and between the upper rear portions of the arm-support H, and may be vibrated about 35 said pivotal connection z and secured in adjustment by turning the set-screw d against the curved bar d' , said arm having its upper end pivotally secured to the back section at d^3 , the free end passed through a loop, d^3 , at the 40 rear lower corner of the arm-support H.

An auxiliary rocking frame, d^4 , by which the seat J may be raised and lowered, and by which the back section, G, and the seat-section J are pivotally secured one to the other, which 45 is also a means for locking the back and seat in adjustment, is provided, consisting of an open V-shaped portion, d^4 , and two arms, d^6 , extending from the V-shaped portion parallel to each other, and is pivotally secured to the 50 sides of the back section near their lower ends and to the sides of the seat-section near their rear ends by suitable bolts or studs, d^7 , which extend through the arms d^6 . The V-shaped portion of the frame when in position 55 is located beneath the seat-section, pointing forward and downwardly. The rock-shaft e is pivotally secured to the seat-frame K, the outer end of the shaft terminating in an operating-crank, L.

On the under side of the seat J there is provided a depending latch, e' , pivotally secured 60 to the seat, said latch having a perforation, e^2 , adapted to receive the end of an arm, e^3 , projecting forwardly from the rock-shaft e and through a perforation, e^4 , in the forward 65 end of rocking frame d^4 , by which the seat

may be locked in adjustment. A laterally-projected handle is provided, by which the latch e' may be swung off the end of the bolt or arm e^3 , to release the frame d^4 and allow 70 the seat to be secured or locked in adjustment.

The seat proper is formed of two sections, J and M, each of which is supported by metal frames K K', joined by hinges e^{10} , and secured in horizontal position by a locking-latch, e^5 , 75 actuated by spring e^6 .

For the purposes of this application I will treat the seat as a whole, referring to the sections J and M as occasion may require.

The front of the seat is secured to the front 80 inner face of the arm-support H at e^7 in a swinging adjustment by means of arms e^8 , e^9 , and f , pivotally secured to each other, as shown. The foot and leg rest section N is hinged to the seat-section M by means of corner-exten- 85 sions, f' , formed with elongated apertures f^2 , which embrace the pivot-bolts f^3 . The extensions f' , after passing the bolts or pins f^3 , are bent at right angles and extend rearwardly a short distance, terminating in open hooks f^4 , 90 adapted to receive short studs f^5 on the inner face of the swinging arm f . The apertures f^2 are sufficiently elongated to admit the extension f' to move upwardly enough to free the hooks f^4 from the studs f^5 and allow the leg 95 and foot rest to depend in a free swinging motion from the bolts or pins f^3 ; but when the hooks are engaged with the studs f^5 the leg and foot rest section will be subject to such movement or changes as are determined 100 by the combined action of the arms e^8 , e^9 , and f .

For the purpose of holding the feet of the patient in suitable position for certain classes of operations, stirrups O are provided and adapted for adjustment by a clamp, P, secured 105 to the arm-support H, by which the stirrups may be adjusted and locked in any desired vertical or angular adjustment, and as a further convenience, by releasing the latch e^5 on the under side of the seat the front section, 110 M, and the leg-rest N may be dropped to position shown in Fig. 5 and again raised to support the patient by raising the leg-rest up, the latch e^5 locking the seat-section in horizontal position, as shown in Fig. 1. 115

To provide for an adjustment or extension of the arm R, a metal plate, S, is provided, having an upwardly-projected rib, g , and slots g' , through which a bolt, g^2 , is passed, by which the plate S is pivotally secured to the arm-support H. An upwardly-projected lug, g^3 , on the arm-support H is adapted to guide the plate S when moved forward and back on the arm-support H. A board, T, which is upholstered, is pivotally secured to the plate S by 120 bolt g^5 and perforation g^6 , on which it may rotate for the purpose of bringing the upholstered portion of the arm R in any desired position. 125

A chair constructed as hereinbefore described may be operated as follows: Presuming the chair to be in normal position, if now

the curved arm d' be released and the back section, g , pressed backward and down, pivoting over the pivotal connection z with the arm-support II, the seat and leg-rest sections 5 may be raised to a horizontal plane, with the back section as shown in Fig. 1, the lower end of the back section swinging forward and up, carrying the seat with it. This movement of the seat-section J will also, by the combined 10 action of the arms e^8 , e^9 , and f and the bent extensions f^3 , with their hooks f^4 engaged with the studs f^5 on the arm f , elevate the leg and foot rest N, in which adjustment the several parts may be secured by tightening the seat- 15 screw d , or in any degree of adjustment or inclination within the limits of vibration. When so adjusted, the body of the chair may be tipped or rocked over its pivotal connection with the frame B by placing the foot on pedal 20 c^5 , pressing down frame a^4 , disengaging the lock e^6 from the rack F, and rocking or tipping the body on the said pivotal connection, and it may be fixed in adjustment by the lock.

25 The body of the chair may be rotated horizontally about its central pivot, b^2 , the frame E resting on the way D, and be locked in adjustment by the set-screw e^9 , or be turned sidewise across the base parallel with the face 30 of the frame B and rocked about in said adjustment by the locking-frame and lock e^6 .

By the construction hereinbefore described a broad and more permanent base for the body of the chair to rotate upon is secured. In 35 the use of the circular way D and the circular body-support E, the locking mechanism being at a greater distance from the center of rotation, the parts may be secured against vibration.

40 By the arrangement of the open frame B sliding vertically in the grooves in the inner face of the base the lifting mechanism may be placed about centrally under the body of the chair, the lifting and locking mechanism 45 rising and falling with the frame B and the short end of the lever C.

Having thus described the nature and object of my invention, what I claim, and desire to secure by Letters Patent, is—

50 1. The combination, in a surgical chair, of a base, A, a frame, B, secured in said base and having a vertically-reciprocating movement, a circular way pivotally secured to said frame, a body-support frame having a circular base resting upon and pivotally secured to said way, a locking-rack depending from said way, and a lock pivotally secured to the frame B and adapted to engage the rack at any desired point of adjustment, substantially as 55 set forth.

60 2. In a chair, the combination of a base, A, a frame, B, secured to said base and having a vertically-reciprocating movement, a circular way pivotally secured to said frame, a body-supporting frame having a circular base pivotally secured to and resting upon the

circular way, upwardly-projected arms, a back pivoted to said arms, a seat-section secured to said arms by pivoted links, devices for swinging said back and seat sections into 70 backwardly and upwardly tilting positions about the axis of the pivotal connection, and devices for locking said back and seat sections in their several adjustments and for locking the body-supporting frame against 75 rotation, substantially as set forth.

3. The combination, in a chair, of a base, A, a frame, B, secured in said base and having a vertically-reciprocating movement, devices in connection with the base A and 80 frame B for raising and lowering said frame and locking it in any desired adjustment, a circular way supported by and pivotally secured to the said frame B, to tilt in a plane vertical to that of the way, a body-supporting 85 frame having a circular base adapted to rest and rotate upon said circular way and provided with upwardly-projecting arms, a back pivoted to said arms, and a seat-section hinged to the back and secured to said arms by 90 pivoted links, substantially as set forth.

4. The combination, with a chair-base and a supporting-frame having a vertically-reciprocating movement in said base, of a combined lifting and lowering foot-lever pivoted 95 to the base, a rack pivoted to said lever and connecting the lever with the reciprocating frame, a locking-bolt carried by the said lever, and a rocking part connected with the foot-lever and locking-bolt, whereby the latter is 100 directly subject to the same impulse which operates the lever, substantially as set forth.

5. The combination, with a chair-base and a supporting-frame having a vertically-reciprocating movement in said base, of a foot-lever, a segmental rack connecting the foot-lever and reciprocating frame, and a locking-bolt having a lengthwise movement relatively 105 to the lever to engage and disengage the said rack and subject to be operated simultaneously therewith, substantially as set forth.

6. The combination, with a chair-base and a supporting-frame having a vertically-reciprocating movement in said base, of a foot-lever, a segmental connection between the 110 foot-lever and vibrating frame, the segmental connection being provided with seats for a locking-bolt and the foot-lever being pivoted to the connection at the center of its segmental arc, a locking-bolt having a movement 115 lengthwise of the lever, and a rocking step connecting the lever and the locking-bolt, substantially as set forth.

7. The combination, in a chair, of a base, A, a frame, B, secured in the said base and having a vertically-reciprocating movement, a circular way pivotally secured to said frame, a chair-body turning on said circular way, and springs, one end of each resting against the frame B and the other against a rack depending from the said way, substantially as 125 set forth.

8. The combination, in a chair, of a base, A,
a frame, B, secured in said base and having
a vertical movement therein, a body-support-
ing frame pivotally secured to said frame B,
5 and springs, one end of each resting against
the frame B and the other against the body-
supporting frame, substantially as set forth.

In testimony whereof I have hereunto set
my hand this 23d day of November, A. D.
1887.

AARON P. GOULD.
